(57) CLAIM

The ornamental design for a multifunctional bag as shown and described.

DESCRIPTION

FIG. 1 is a front and right perspective view showing of a multifunctional bag showing our new design;
FIG. 2 is a front and left perspective view thereof;
FIG. 3 is a rear and left perspective view thereof;
FIG. 4 is a rear and right perspective view thereof;
FIG. 5 is a rear and bottom perspective view thereof;
FIG. 6 is a front elevational view thereof;
FIG. 7 is a rear elevational view thereof;
FIG. 8 is a right side elevational view thereof;
FIG. 9 is a left side elevational view thereof;
FIG. 10 is a top plan view thereof;
FIG. 11 is a bottom plan view thereof;
FIG. 12 is a front and right perspective view of the multifunctional bag in an alternative state;
FIG. 13 is a front and left perspective view thereof;
FIG. 14 is a rear and left perspective view thereof;
FIG. 15 is a rear and right perspective view thereof;
FIG. 16 is a rear and bottom perspective view thereof;
FIG. 17 is a front elevational view thereof;
FIG. 18 is a rear elevational view thereof;
FIG. 19 is a right side elevational view thereof;
FIG. 20 is a left side elevational view thereof;
FIG. 21 is a top plan view thereof; and,
FIG. 22 is a bottom plan view thereof.
